Primary Examiner—Ralf Seifert*Attorney, Agent, or Firm*—Trask, Britt & Rossa[57] **CLAIM**

The ornamental designs for a lanyard, as shown and described.

DESCRIPTION

FIG. 1 is a perspective view of a lanyard according to the invention;

FIG. 2 is a top plan view of the lanyard of FIG. 1;

FIG. 3 is a right side view of the lanyard of FIG. 2; the left side being a mirror image thereof;

FIG. 4 is a bottom plan view of the lanyard of FIG. 1;

FIG. 5 is a top plan view of the lanyard of FIG. 2 with the connection member being shown in a disengaged condition;

FIG. 6 is a right side view of the lanyard of FIG. 5; the left side being a mirror image thereof;

FIG. 7 is a top plan view of a second embodiment of the lanyard of the invention;

FIG. 8 is a right side view of the lanyard of FIG. 7; the left side view being a mirror image thereof;

FIG. 9 is a bottom plan view of the lanyard of FIG. 7;

FIG. 10 is a top plan view of a third embodiment of the lanyard of the invention;

FIG. 11 is a right side view of the lanyard of FIG. 10; the left side view being a mirror image thereof;

FIG. 12 is a bottom plan view of the lanyard of FIG. 10.

FIG. 13 is a perspective view of a fourth lanyard according to the invention;

FIG. 14 is a top plan view of the lanyard of FIG. 13, the bottom plan view being a mirror image thereof;

FIG. 15 is a right side view of the lanyard of FIG. 13; the left side being a mirror image thereof;

FIG. 16 is a top plan view of the lanyard of FIG. 13 with the connection member being shown in a disengaged condition;

FIG. 17 is a right side view of the lanyard of FIG. 16; the left side being a mirror image thereof;

FIG. 18 is a top plan view of a fifth embodiment of the lanyard of the invention;

FIG. 19 is a right side view of the lanyard of FIG. 18; the left side view being a mirror image thereof;

FIG. 20 is a top plan view of a sixth embodiment of a lanyard of the invention, the bottom view being a mirror image thereof; and,

FIG. 21 is a right side view of the lanyard of FIG. 20; the left side view being a mirror image thereof.
